US0D1086193S

(12) **United States Design Patent** (10) **Patent No.:** **US D1,086,193 S**
(45) **Date of Patent:** **** Jul. 29, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Christian Xavier Dalonzo**, San Francisco, CA (US); **Chanaka Karunamuni**, San Jose, CA (US)

(73) Assignee: **Apple Inc.**, Cupertino, CA (US)

(**) Term: **15 Years**

(21) Appl. No.: **29/987,446**

(22) Filed: **Jan. 23, 2025**

Related U.S. Application Data

(63) Continuation of application No. 29/853,766, filed on Sep. 19, 2022, now Pat. No. Des. 1,059,382, which is a continuation of application No. 29/829,694, filed on Mar. 7, 2022, now Pat. No. Des. 964,396, which is a continuation of application No. 29/738,902, filed on Jun. 20, 2020, now Pat. No. Des. 947,866.

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.

The FIGURE is illustrated to show contrasting appearance. Areas of the display or portion thereof with graphical user interface that appear in different shades of gray represent areas with contrasting appearances.
